UNITED STATES PATENT OFFICE

93,134

DESIGN FOR A BUILDING

Luther B. Robertson, Matador, Tex.

Application January 10, 1934, Serial No. 50,367

Term of patent 7 years

To all whom it may concern:

Be it known that I, LUTHER B. ROBERTSON, a citizen of the United States, residing at Matador, in the county of Motley and State of Texas, have invented a new, original, and ornamental Design for a Building, of which the following is a specification, reference being had to the accompanying drawing, forming part thereof.

Figure 1 is a view in front elevation of a building, showing my new design.

Figure 2 is a side elevational view thereof.

I claim:

The ornamental design for a building as shown.

LUTHER B. ROBERTSON.
